UNITED STATES PATENT OFFICE.

EDWIN M. GOLDSMITH AND HENRY F. GOLDSMITH, OF PHILADELPHIA, PENNSYLVANIA, ASSIGNORS TO FRIEDBERGER-AARON MANUFACTURING COMPANY, OF PHILADELPHIA, PENNSYLVANIA, A CORPORATION OF PENNSYLVANIA.

GARTER PACKING AND EXHIBITING DEVICE.

Application filed February 15, 1927. Serial No. 168,270.

The object of the invention is to provide a means for displaying articles of merchandise, and particularly knitted or woven goods, such as garters, which should be open to inspection and yet protected from dust and dirt and from being soiled by handling. Such articles are usually wrapped in transparent paper and are so secured in multiple on a card mount that they may be separately readily removed.

Our invention comprises a new and useful device of this character, one preferred embodiment of which is shown in the accompanying drawings, in which—

Fig. 1 is a front view of a card mount with one of our garter holders mounted thereon.

Fig. 2 is a view of the blank for the garter holder.

Figs. 3 and 4 are end views showing how the blank is folded to form the holder.

Fig. 5 is a rear view of the folded holder.

Fig. 6 is a rear view, and Fig. 7 an end view, of the finished holder.

Fig. 8 is a rear view, Fig. 9 an end view, and Fig. 10 a side view of the holder of Figs. 6 and 7 with a strip applied thereto for adapting the holder to be mechanically interlocked with the card mount.

Fig. 11 is an enlarged cross-section through the card and one of the holders.

A sheet of cardboard is scored along four lines so as to adapt it to be folded to form the front *a*, a back *b*, *b'* and sides *c*, *c'* of a holder. If the article of merchandise is a pair of garters *x*, the same are slipped over the holder, before it is folded as described until they engage and enclose the front *a*. The combined width of two wings *b*, *b'* of the back is greater than that of the front so that, when the parts are folded as described, the edges of the wings overlap; and in order that they may also interlock, one of the wings is provided with a notch *d* with which the other wing is adapted to engage in such manner that each wing overlaps the other for half the height of the holder.

To maintain the holder in its folded and operative condition, a "sticker" *e* of paper or fabric is applied to the back of the card so as to overlap the joints between the two wings *b*, *b'*, being preferably glued thereto.

The holder, with the garters carried thereby, is then enclosed in a sheet of transparent paper *f*. The paper need not, and preferably does not, cover the back of the holder but

should merely cover the marginal edges 55 thereof.

It is impossible to effectively glue the ordinary transparent paper of commerce to a cardboard surface unless such paper is already mounted on a flat stiff material. It is 60 possible, therefore, to glue the back of the holder herein described direct to a card mount, whether the transparent paper extends entirely across the back or only along the marginal part thereof, but if, as is preferred, 65 the transparent paper does not engage the back of the holder except adjacent the edges, the glue is applied directly to the sticker *e*, which is directly glued to the card mount.

70

An alternative way of securing the holder to the card mount is to secure to the back of the holder a strip *g* which may be flush with one edge of the holder and which is provided with a tongue *h* that extends beyond the 75 holder. The strip *g* should be secured to the holder relatively near its ends only and not along that part thereof adjacent the tongue *h*. The card mount *m* is provided with a tongue *i* enclosed on three sides by a slot *j*. The tongue *h* of the holder is adapted to be slipped into the slot *j* and under the tongue *i*, which is adapted to extend between the strip *g* and the back of the holder, as shown in Fig. 11. Thereby the holder is mechanically interlocked with the card mount.

Whether the holder is glued to, or mechanically engaged with, the card mount, it may be readily removed for delivery to a pur- 80

85

chaser.

90

Having now fully described our invention, what we claim and desire to protect by Letters Patent is:

1. A contrivance for displaying articles of merchandise, comprising a holder consisting 95 of a sheet of cardboard bent to provide a shallow open-ended structure adapted to engage and support an article of merchandise, the front of the holder being formed by the central part of the sheet and the back of the 100 holder being formed of the parts of the sheet adjacent to the latter's opposite edges, said parts overlapping and interlocking, a transparent wrapper covering the front and enclosing the open ends of the holder, a strip 105 secured relatively near its ends to the back of the holder along one edge thereof, and a card mount cut away to form a tongue partly

surrounded by a slot, said holder being so engaged on the card mount that the tongue of the latter extends between the back of the holder and the mediate part of the strip not secured to the holder.

2. A display package comprising a holder consisting of a sheet of cardboard bent to provide a shallow open ended structure, the front of the holder being formed by the central 10 part of the sheet and the back of the holder being formed of the parts of the sheet adjacent to the latter's opposite edges, said parts overlapping and interlocking, in combination with a tubular article of merchandise extending between the front and back of the holder and from the open ends thereof about the outside of the front, and a transparent wrapper covering the front of the holder, the open sides thereof and the article of merchandise carried thereby.

3. A display package comprising a holder

consisting of a sheet of cardboard bent to provide a shallow open ended structure, the front of the holder being formed by the central part of the sheet and the back of the holder being formed of the parts of the sheet adjacent to the latter's opposite edges, said parts overlapping and interlocking, in combination with a tubular article of merchandise extending between the front and back of the holder and from the open ends thereof about the outside of the front, a transparent wrapper covering the front of the holder, the open sides thereof and the article of merchandise carried thereby, and a sticker securing the 30 parts of the back of the holder together. 35

In testimony of which invention, we have hereunto set our hands, at Philadelphia, Pennsylvania, on this 11th day of February, 1927.

EDWIN M. GOLDSMITH.
HENRY F. GOLDSMITH.
